UNITED STATES PATENT OFFICE.

CARL G. SPRADO, OF MILWAUKEE, WISCONSIN, ASSIGNOR TO ALLIS-CHALMERS MANUFACTURING COMPANY, OF MILWAUKEE, WISCONSIN, A CORPORATION OF DELAWARE.

ENGINE CYLINDER.

Application filed July 19, 1926. Serial No. 123,585.

This invention relates to improvements in the construction and in the mode of manufacturing cylinders for machines such as fluid pressure operated prime movers or compressors.

An object of the invention is to provide a new and useful cylinder structure for engines or machines such as prime movers or compressors. Another object of the invention is to provide an improved method of manufacturing cylinders in order to adapt the same to withstand extreme variations in temperature, without destruction. A further object of the invention is to provide simple and efficient means for strengthening the structure of cast cylinders or the like.

Considerable difficulty has heretofore been experienced in the construction of cylinders for prime movers such as internal combustion engines, in providing a cylinder structure adapted to withstand the service to which such apparatus is ordinarily subjected. A gas engine cylinder is of necessity a complicated casting, which is required to withstand enormous stresses due to the combustion or explosion of gases therein, and also due to the variations in temperature to which it is subjected in service. Cast cylinders of this type, are also subjected to enormous stresses resulting from uneven cooling and contraction of the casting in the mold, during formation of the cylinders. It is an object of the present invention to provide an improved cylinder structure especially applicable to large engine or pump cylinders, which will effectively accommodate or resist any normal stresses to which it may be subjected either during construction thereof or during subsequent operation of the machine.

A clear conception of an embodiment of the invention and of the mode of constructing cylinders in accordance therewith, may be had by referring to the drawings accompanying and forming a part of this specification in which like reference characters designate the same or similar parts in the various views.

Fig. 1 is a central vertical section through an improved engine cylinder especially applicable to gas engines.

Fig. 2 is a part sectional top view of the improved gas engine cylinder.

Fig. 3 is a transverse vertical section

through the improved gas engine cylinder, 55 the portion to the right of the center line of the figure being a section through the medial portion of the cylinder, and the other half of the figure illustrating a section through an end portion of the cylinder. 60

Fig. 4 is a part sectional top view through another form of gas engine cylinder embodying the invention.

Fig. 5 is a transverse vertical section 65 through the medial and end portions of the cylinder disclosed in Fig. 4.

Fig. 6 is a transverse vertical section through the medial and end portions of another form of cylinder embodying the invention. 70

Fig. 7 is a fragmentary transverse vertical section through the medial and end portions of still another form of cylinder embodying the invention.

Referring specifically to Figs. 1 to 3 inclusive, the gas engine cylinder comprises in general an annular inner wall 2 forming a combustion chamber 11, and an outer wall 3 surrounding and spaced from the inner wall 2 to form an annular jacket space 12. 75 The outer cylinder wall 3 is provided with upper and lower end openings, and inlet and discharge valve pockets 4, 10 respectively, are cast integral with the inner wall 2 and extend outwardly therefrom across the jacket 80 space 12 to points within the end openings of the outer wall. The valve pockets 4, 10 while being cast integral with the inner wall 2 are preferably free from direct cast connection with the outer wall 3. An annular 85 series of ribs 5 are cast integral with and connect the inner and outer walls 2, 3 intermediate the valve pockets. The ribs 5 extend longitudinally of the cylinder and are formed relatively thin so as to make them 90 laterally deflectable. A plurality of radially disposed spacing members 6 are also cast integral with the inner and outer walls 2, 3 adjacent to the valve pockets 4, 10, these members 6 being relatively thin and hence 95 deflectable longitudinally of the cylinder axis. The ribs 5 and members 6 while spanning the jacket space 12, still allow free circulation of cooling medium through this 100 jacket. As illustrated in Figs. 1 to 3 inclusive of the drawing, the ends of the walls 2, 3 are also free from direct cast connection 105 and the annular spaces between the wall ends

are closed by means of end plates 7. The annular spaces between the outer ends of the inlet valve pockets 4 and the outer wall 3 are also closed by means of top plates 8, and the spaces between the exhaust valve pockets 10 and the outer wall 3 are likewise closed by means of bottom plates 9. The closure plates 7, 8, 9 seal the jacket space 12 against possible escape of cooling fluid which may be admitted and discharged from the jacket in a well known manner.

Referring specifically to Figs. 4 and 5, the gas engine cylinder disclosed therein comprises in general an annular inner wall 13 forming a combustion chamber 21, and an outer wall 14 surrounding and spaced from the inner wall 13 to provide an annular jacket space 22. The outer wall 14 has upper and lower end openings, and inlet and discharge valve pockets 15, 19, respectively, are cast integral with the inner wall 13 and extend outwardly therefrom across the jacket space 22 to points within the end openings of the outer wall 14. The valve pockets 15, 19 while being cast integral with the inner wall 13 are preferably free from direct cast connection with the outer wall 14. An annular series of inclined or tangential ribs 16 are cast integral with and connect the inner and outer walls 13, 14, intermediate the valve pockets 15, 19. The ribs 16 extend longitudinally of the cylinder and are formed relatively thin thus making them transversely deflectable. A plurality of radially disposed spacing members or stay bolts 17 have their ends cast into or integral with the inner and outer cylinder walls adjacent to the valve pockets 15, 19, these bolts being laterally deflectable to permit relative shifting of the walls. The ribs 16 and the bolts 17 while spanning the jacket space 22 and forming a resilient connection between the inner and the outer wall, permit free circulation of cooling medium through the jacket. The extreme ends of the inner and outer walls 13, 14 may be connected by relatively thin end walls 18 which are cast integral with the cylinder walls but are deflectable longitudinally of the cylinder axis. The annular spaces between the outer ends of the inlet valve pockets 15, 19 and the outer wall may be closed by means of plates as shown in Fig. 1, and the walls 13, 14 may be provided with spark plug receiving openings 20 as shown in the drawing.

In the embodiment of the invention specifically illustrated in Fig. 6, an annular inner wall 23 forms the combustion chamber 31 and is surrounded by a partially polygonal and partly substantially circular outer wall 24 spaced from the inner wall 23 to form an annular jacket space 32. The circular end portions 30 of the outer wall 24 are provided with upper and lower end openings, and inlet and discharge valve pockets 25, 28 which are

cast integral with the inner wall 23 extend outwardly therefrom across the jacket space 32 to points within the end openings of the outer wall 24. The valve pockets 25, 28 are free from direct cast connection with the outer wall portions 30 and the annular openings between the valve pockets and the outer wall may be closed by means of plates as in Fig. 1. An annular series of radially disposed ribs 26 are cast integral with and connect the inner wall with the medial portions of the flat sides of the polygonal medial portion of the outer wall 24, these ribs 26 extending longitudinally of the cylinder and being laterally deflectable. A plurality of radially disposed spacing members or stay bolts 27 have their ends cast into the inner wall 23 and into the circular outer wall portion 30 located adjacent to the valve pockets 25, 28, these stay bolts also being laterally deflectable. The ribs 26 and the members or bolts 27 merely connect and provide resilient spacers for the inner and outer walls 23, 24 and do not obstruct the free circulation of cooling medium through the jacket. The ends of the inner and outer walls 23, 24 may be separated as shown in Fig. 1 or they may be joined by end walls as in Fig. 4, and the cylinder walls may be provided with spark plug openings 29 as shown.

In the embodiment of the invention specifically illustrated in Fig. 7, the annular inner wall 33 forms a combustion chamber 41, and is surrounded by a partially serrated and partly substantially circular wall 34 which is spaced from the inner wall 33 to form a jacket space 42. The circular end portions 40 of the outer wall 34 are provided with upper and lower openings, and inlet and discharge valve pockets 35 which are cast integral with the inner wall 33 extend outwardly from this wall across the jacket space 42, to points within the openings of the outer wall portions 40. The valve pockets 35 are free from direct cast connection with the outer wall portions 40 and the annular spaces separating the valve pockets from the outer wall may be closed by plates as previously indicated. An annular series of radially disposed ribs 36 connect the inner wall with the innermost portions of the serrated medial portion of the outer wall 34 and extend longitudinally of the cylinder, the ribs 36 being laterally deflectable. A plurality of radially disposed spacing members or stay bolts 37 having their inner ends cast into the inner and outer walls respectively, are located adjacent to the valve pockets 35, these stay bolts likewise being laterally deflectable. The resilient ribs 36 and stay bolts 37 cooperate to connect and to properly space the inner and outer walls 33, 34, and do not obstruct the free circulation of cooling medium through the jacket

space. The ends of the inner and outer walls 33, 34 may be separated as in Fig. 1, or they may be joined by end walls as in Fig. 4, and the cylinder walls may be provided 5 with spark plug openings 39 as shown.

When the cylinders shown in the drawing are applied to internal combustion or gas engines, the explosions or combustion of the gases tend to heat the inner walls to 10 an extremely high degree. In order to reduce to a minimum the temperature of the inner walls, cooling medium such as water is circulated through the jacket spaces thereby producing considerable difference in temperature between the inner and outer walls. Since the explosions occur periodically, there 15 is alternate heating and cooling of the inner wall, and the rise in temperature may also vary in accordance with variations in the characteristics of the explosive mixture admitted to the engine. In order to avoid destruction of the cylinder due to such variations in temperature between the outer and the inner walls, it is desirable to provide 20 for relative expansion and contraction of these walls. Due to the enormous pressures within the combustion chambers of such cylinders, it is however necessary to utilize the outer wall to externally brace the inner wall. 25 Because of the complicated nature of the structure, the casting of such cylinders is also made difficult on account of the unequal stresses set up in the various portions of the structure. The outer and inner walls 30 may not cool at a uniform rate thereby producing enormous stresses in the connections between these walls. Any connections provided should therefore be sufficiently resilient to permit relative expansion and contraction between the walls during construction 35 of the cylinders, as well as during normal operation.

It will be apparent that with the embodiment of the invention illustrated in Figs. 45 1, 2 and 3, the outer and inner walls are free to expand and contract independently of each other. The laterally deflectable longitudinal ribs 5 permit relative displacement of the walls 2, 3 at the medial portion 50 of the cylinder, while the deflectable member 6 permit free relative expansion of the walls at the cylinder ends. The valve pockets 4, 10 which are free from direct cast connection with the outer wall 3, likewise permit 55 free relative expansion and contraction of the walls in any direction without danger of cracking the casting.

The embodiments of Figs. 4, 5, 6 and 7 60 also permit free relative expansion and contraction of the inner and outer walls in an obvious manner. The deflectable ribs 16, 26, 36 permit free relative displacement of the inner and outer walls at the medial portion 65 of the cylinder, while the resilient stay bolts 17, 27, 37 permit relative displacement of

these walls both about and along the axis at the cylinder ends. As in the case of Fig. 1, the valve pockets 15, 19, 25, 28, 35 are free from direct cast connection with the outer walls thereby permitting free relative displacement of the walls about and along the cylinder axis. The tangential ribs 16 of Fig. 5 while serving as efficient struts between the two walls merely produce relative displacement of these walls about the cylinder axis when the ribs 16 expand or contract. With the polygonal form of cylinder illustrated in Fig. 6, expansion of the ribs 16 will merely tend to curve the normally straight sides of the polygon and contraction will tend to straighten these sides. With the serrated form of outer wall disclosed in Fig. 7, expansion and contraction of the ribs 36 will be accommodated in an obvious manner, at the outermost portions 85 of the serrations.

It will be thus be noted that the invention provides simple and efficient means for effectively accommodating normal stresses to which the cylinder structure may be subjected either during construction thereof or during subsequent operation of the machine. The connections effectively brace the inner wall against excessive pressures and do not interfere with the circulation of cooling 90 medium through the jacket space. The valve pockets may be cast integral with either wall, but are preferably so attached to the inner wall in order to avoid leakage of the cooling medium into the combustion 95 chamber. The annular openings surrounding the valve pocket ends and at the cylinder ends also facilitate supporting of the jacket cores.

It should be understood that it is not 100 desired to limit the invention to the exact details of construction herein shown and described for various modifications within the scope of the claims may occur to persons skilled in the art.

It is claimed and desired to secure by Letters Patent:

1. In an engine cylinder, inner and outer walls cooperating to form an intervening space, a valve pocket spanning said space, said pocket being rigidly attached to one of said walls and being free from direct connection with the other, and means rigidly connecting medial portions of said walls and formed to permit free relative longitudinal expansion of the end portions thereof.

2. In an engine cylinder, inner and outer annular walls cooperating to form an intervening space surrounding said inner wall, a plurality of valve pockets spanning said space adjacent to the ends of said walls, said pockets being rigidly attached to said inner wall and being free from direct connection with said outer wall, and means rigidly connecting medial portions of said

walls and formed to permit free relative longitudinal expansion of the wall ends adjacent to said pockets.

3. In an engine cylinder, inner and outer walls cooperating to form an intervening space, a valve pocket spanning said space, said pocket being cast integral with one of said walls and being free from direct cast connection with the other wall, and a member cast integral with and connecting said walls remote from said pocket, said member being formed to permit free relative longitudinal expansion of said walls adjacent to said pocket.

4. In an engine cylinder, inner and outer annular walls cooperating to form an intervening space surrounding said inner wall, a valve pocket spanning said space adjacent to the ends of said walls, said pockets being cast integral with said inner wall and being free from direct cast connection with said outer wall, and a member direct connecting and cast integral with said walls between said pockets, said member being formed to permit free relative longitudinal expansion of said walls adjacent to said pockets.

5. In an engine cylinder, inner and outer walls cooperating to form an annular intervening space surrounding said inner wall, valve pockets spanning said space adjacent to the ends of said walls said pockets being cast integral with one of said walls and being free from direct cast connection with the other, a rib extending longitudinally of the axis of said cylinder and direct connecting said walls between said pockets, and a member direct connecting said walls adjacent to each of said pockets.

6. In an engine cylinder, inner and outer walls cooperating to form an annular intervening space surrounding said inner wall, valve pockets spanning said space adjacent to the ends of said walls, said pockets being cast integral with said inner wall and being free from direct cast connection with said outer wall, ribs extending longitudinally of said cylinder and connecting said walls between said pockets, and members connecting said walls on opposite sides of said ribs, said members being deflectable in a direction longitudinally of said cylinder.

7. In an engine cylinder, inner and outer walls cooperating to form an annular intervening space surrounding said inner wall, valve pockets spanning said space on opposite sides of the cylinder axis and adjacent to the ends of said walls, each of said pockets being cast integral with said inner wall and being spaced from said outer wall, a plurality of ribs extending longitudinally of said cylinder and connecting said walls between said pockets, and a plurality of members direct connecting said walls on opposite sides of said ribs, said ribs being deflectable about the axis of said cylinder and

said members being deflectable longitudinally of said axis.

8. In an engine cylinder, an inner wall having valve pockets cast integral therewith and extending outwardly therefrom, an outer wall surrounding said inner wall and having openings therein spaced from the outer ends of said valve pockets, and ribs directly connecting said walls and maintaining a spaced relation therebetween independently of said valve pockets, said ribs being formed to permit free relative longitudinal expansion of said walls adjacent to said pockets.

9. In an engine cylinder, an inner annular wall having a plurality of valve pockets cast integral therewith and extending outwardly therefrom, an outer wall surrounding said inner wall to form an intervening space and having openings spaced from the outer extremities of said pockets, a plurality of ribs cast integral with said walls between said pockets, and a plurality of spacing members connecting said walls adjacent to said pockets, said members being laterally deflectable longitudinally of the cylinder axis to permit relative longitudinal expansion of said walls adjacent to said pockets.

10. In an engine cylinder, an inner annular wall having a plurality of valve pockets cast integral therewith and extending outwardly therefrom, an outer wall surrounding said inner wall to form an intervening space and having openings spaced from the outer extremities of said pockets, a plurality of ribs cast integral with said walls between said pockets, and a plurality of spacing members connecting said walls adjacent to said pockets, said ribs being deflectable about the axis of said cylinder and said members being deflectable longitudinally of said axis.

11. In an engine cylinder, inner and outer walls cooperating to form an annular intervening space, a plurality of ribs cast integral with the medial portion of both of said walls and extending longitudinally of the cylinder, and a plurality of radially disposed members connecting said walls at the ends of said ribs.

12. In an engine cylinder, an inner wall, an outer wall surrounding said inner wall and spaced therefrom to form an annular intervening open ended space, and a plurality of ribs cast integral with both of said walls and disposed within said space, said ribs being located remote from the ends of said walls to permit relative longitudinal expansion of said walls at said ends.

13. In an engine cylinder, an annular inner wall, an outer wall surrounding and cooperating with said inner wall to form an annular space, a rib direct connecting the medial portions of said walls and extending longitudinally of the cylinder, and a radial

member direct connecting said walls at an end thereof.

14. In an engine cylinder, an inner annular wall, an outer annular wall surrounding said inner wall and spaced therefrom to form an annular intervening space, said walls being free from direct connection adjacent to their ends, and a plurality of spacing members rigidly connecting medial portions of said walls within said space, said members being formed to permit free relative longitudinal expansion of said walls adjacent to said ends. 10
15. In an engine cylinder, an inner wall, an outer wall surrounding said inner wall 15 and spaced therefrom to form an annular intervening space, said walls being free from direct connection adjacent to their ends, and a plurality of radially disposed spacing members cast integral with both of said walls 20 intermediate said ends, said spacing members being laterally deflectable longitudinally of the cylinder axis to permit relative longitudinal expansion of said walls at said ends. 25

In testimony whereof, the signature of the inventor is affixed hereto.
